JULIUS EDGAR LILIENFELD, OF WINCHESTER, MASSACHUSETTS

CATHODE FOR ELECTROLYTIC CONDENSERS

Application filed June 19, 1930. Serial No. 462,254.

The invention relates to electrical condensers of the electrolytic type, and to a novel method of operating the same.

In the operation of electrolytic condensers, it has been found desirable in many cases to constitute the cathode of the condenser of the same metal as that of which the anode is composed for the purpose of preventing contamination of the electrolyte by the introduction of large amounts of foreign matter. Disturbances in the operation, however, have resulted especially when aluminum has been utilized as the particular metal. For example, it has been found that the impedance of a condenser would increase if operated on A. C. voltages; and if the condenser be utilized in D. C. circuits, as for filtering purposes, the efficiency would drop appreciably.

In explanation of these phenomena, the view has been advanced that an aluminum cathode will film, even at a high negative potential, if an A. C. component—pulsating voltage or ripple—is present in the circuit. This conception led to rather expensive expedients where a metal container for the electrolyte was intended for use as the cathode. For example, such containers were made of pure copper; or, the cathode would be constituted of a large area of aluminum alloy possessing enough foreign additions to obviate the filming action under the low current densities.

I have found that the physical reason for the difficulty indicated above has nothing in common with the pulsations of the voltage at the cathode, the correct explanation being that the potential of the electrolyte, which is always negative with respect to the anode, may incidentally drop sufficiently to become slightly negative with respect to the cathode.

When the cathode is then of a filming material, this will result in the formation of a film thereon which, in turn, will cause the potential of the electrolyte to become more negative. This will continue and the potential

distribution will be in unstable equilibrium until the cathode is covered by the ultimate amount of film.

It is the object of the present invention to obviate such action; and in operating the novel condenser the electrolyte and cathodic electrode of such condenser are maintained at equi-potential by discharging from said electrolyte to the cathodic electrode charges developing potentials negative thereto. This may conveniently be effected by extending into the electrolyte from the cathodic electrode a "sounder" member of a non-filming metal, which "sounder" short-circuits the electrolyte, therefore, to the said electrode so that the former will never be permitted to become negative with respect to the latter. The area of this sounder member may be extremely small relatively to the area of the cathodic electrode in view of the small charges which it has to accommodate. Its presence, moreover, will enable the entire area of the said electrode to remain active.

The nature of the invention, however, will best be understood when described in connection with the accompanying drawing, which is a vertical section through the novel condenser.

As indicated, the condenser comprises a container, in the present instance constituted by the cathode 1 which, for example, may be of aluminum. The said container retains a suitable electrolyte 2 and is of the nature of an open-ended cylinder sealed at its opposite ends in any suitable manner, for example, as set forth in my co-pending application, Serial No. 462,250 for Electrolytic Condenser filed of even date herewith.

The anode 3 of the condenser is then also of aluminum and is provided with the terminal 4 passing through the bottom of the container for operation of said condenser with total immersion of the anode in the electrolyte as is also set forth in the aforesaid co-pend-

ing application, and the top of the container is provided with a suitable vent 5.

While the foregoing construction is novel in certain respects, so far as the present invention is concerned it is immaterial whether this particular type of condenser be utilized or whether the same be of the standard type, the invention consisting in the provision of means in connection with the cathode or container element 1 for short-circuiting the same to the electrolyte 2 in order to maintain at all times the latter at the same potential as the former.

This may be effected in a simple manner merely by introducing a metallic "sounder" member which projects into the electrolyte from the said cathode 1 so that the latter may impart a charge by means of said "sounder" to the said electrolyte for preventing the electrolyte becoming more negative than the said cathode. I have found that by securing a copper rivet 6, of negligible size relatively to the cathode, through the wall of the said cathode 1, this effect may readily be accomplished as the inner head of the rivet will be in direct contact with the electrolyte while at least its shank and outer head are in contact with the cathode.

I claim:

30 1. In an electrolytic condenser comprising a metallic container for electrolyte and an anodic electrode therein, the container being of the same metal as the anodic electrode and constituting the cathodic electrode therefor: 35 a sounder of a non-filming metal short-circuiting the electrolyte to the cathodic electrode.

2. In an electrolytic condenser comprising a metallic container for electrolyte and an 40 anodic electrode therein, the container being of the same metal as the anodic electrode and constituting the cathodic electrode therefor: a sounder of a non-filming metal short-circuiting the electrolyte to the cathodic electrode and of area relatively small with respect to that of said cathodic electrode.

3. In an electrolytic condenser comprising an aluminum container for electrolyte and constituting the cathodic electrode of the condenser, and an aluminum anodic electrode 50 therein: a sounder of a non-filming metal projecting therein from the container and short-circuiting the electrolyte to said container.

55 4. In an electrolytic condenser comprising an aluminum container for electrolyte and constituting the cathodic electrode of the condenser, and an aluminum anodic electrode therein: a sounder of copper projecting therein from the container and short-circuiting the electrolyte to said container.

65 5. In an electrolytic condenser comprising an aluminum container for electrolyte and constituting the cathodic electrode of the condenser, and an aluminum anodic electrode

therein: a rivet of a non-filming metal passing through the wall of the container into the electrolyte and short-circuiting the same to said container.

6. In an electrolytic condenser comprising 70 an aluminum container for electrolyte and constituting the cathodic electrode of the condenser, and an aluminum anodic electrode therein: a copper rivet passing through the wall of the container into the electrolyte and 75 short-circuiting the same to said container.

In testimony whereof I affix my signature.
JULIUS EDGAR LILIENFELD.
